PROCESS OF PRODUCING SUBSTANTIALLY
PURE MAGNESIUMFritz Hansgirg, Radenthein, Austria, assignor
to American Magnesium Metals Corporation,
Pittsburgh, Pa., a corporation of DelawareApplication December 28, 1933, Serial No. 704,298
In Austria January 17, 1933

6 Claims. (Cl. 75—17)

This application is a continuation in part of my application Ser. No. 655,067, filed February 3, 1933.

5 My invention relates to a process of and apparatus for producing substantially pure magnesium.

One object of the present invention is to separate substantially pure magnesium from non-volatile concomitant substances.

10 Another object of my invention is to enable magnesium to be distilled so as to condense the distillate as a liquid deposit.

A further object of the invention is to provide a process of and apparatus for the distillation of 15 material containing metallic magnesium which can be carried on continuously.

The process forming the subject matter of my application Ser. No. 655,067 comprises passing crude metallic magnesium or magnesiferous material high in magnesium through a heated zone in which magnesium is vaporized under the prevailing pressure conditions, removing the resulting vapor by a non-oxidizing gas from the heated zone, separating out dusty impurities from said 25 vapor, thereafter passing the vapor into a condensation zone, and cooling it to the condensation point. The vapor is preferably prevented from cooling below the solidification point of the magnesium by being heated on its way to the condensing zone, and is then suddenly cooled to condensation point.

The process performed in this manner has special reference to the refining of magnesium by distillation in a continuous working operation, the 35 metal being condensed as a liquid deposit of maximum purity. If desired this process may be performed at reduced pressure.

While various types of apparatus might be employed for carrying out this process, a typical 40 apparatus according to the original invention consists substantially of an externally heated distillation still, which is provided with a conveyor and connected, by means of a heated pipe line, with a condenser from which the molten 45 magnesium runs off into a collector, for example, through a barometric discharge, a filter being interposed between the said distillation chamber and the said condenser. The still, pipe line, filter, condenser, discharge and receiver are preferably housed in a common heating chamber, such 50 as an electric radiation furnace.

According to the present invention, the magnesium vapors issuing from the distillation chamber are freed from impurities present in the form 55 of dust while passing to the condenser by using

for this purpose the known principle of dust removal by reversing the direction of flow and/or reducing the velocity of flow of the vapors. By replacing filtration by such a method of removing dust the vapors merely encounter a small resistance which remains unchanged during the entire period of working and does not therefore give rise to any irregularities during the process. Moreover the thermal economy of the process is improved because preheating the fresh filtering 10 material required for replenishing consumed material when using granular filters, is dispensed with.

For carrying out the present process dust removing apparatus of known construction in which 15 the dust is precipitated by the principle of reversal of the direction of flow and/or of reducing the velocity of flow, for example dust precipitators with baffle plates or centrifugal (cyclone) gas cleaners can be inserted between the distillation 20 chamber and the condenser; the dust removing chambers of this apparatus must, however, be heated in order to prevent any condensation of the metal vapors in the dust precipitators.

In order to complete the operation of the re- 25 removal of dust two or more such apparatus of identical or different construction can be placed side by side or dust precipitating chambers can be arranged in series in the path of flow of the vapors.

30 In order more clearly to understand the nature of the invention, reference is made to the accompanying drawings, which illustrate diagrammatically and by way of example, an embodiment of apparatus suitable for carrying out the process 35 of the invention.

In said drawings Fig. 1 is a vertical section taken on line I—I of Fig. 3; Fig. 2 a horizontal section along the line II—II of Fig. 1; Fig. 3 a longitudinal section showing means for feeding 40 the material continuously.

A pipe 2 leads from the middle of the distillation chamber 1, through which the material to be distilled is continuously fed, tangentially into a cylindrical dust precipitating chamber 3, which 45 tapers conically in a downward direction. The lower end of the chamber is connected with the dust collecting space 4. The vertical limb of a bent pipe 5 passes through the centre of the cover of the chamber 3 and constitutes the connection 50 between said chamber and the condenser 6. The vapors bathe the jacket of the hollow vessel 7, whereon condensation proceeds, the liquid metal being collected in the receiver.

The dust contained in the vapors which enter 55

the dust-removing chamber 3 is precipitated chiefly on the cylindrical jacket of the chamber by the action of centrifugal force and falls into the collecting space 4, whilst purified vapors pass 5 on to the condenser via pipe 5.

The distillation can be effected either with or without the aid of reduced pressure.

The distillation chamber 1, dust separator 3, condenser 6, and the pipes connecting them are 10 disposed within a heating furnace 8, as referred to hereinabove, for example of the electric radiation type.

Various means may be used for moving the material to be distilled continuously through the 15 distillation chamber, that shown being one of the means disclosed in my aforesaid application Serial No. 655,067. Having reference to Fig. 3, distillation chamber 1 is in the form of an elongate tube in which there is mounted a screw conveyor 20 9 to which the material to be distilled is fed from a charging hopper 10 supplied with material from a storage bin 11 through a lock chamber 12 controlled by valves 13 and 14, so that material may 25 be charged into hopper 10 from storage bin 11 while preventing entry of air into the distillation apparatus. The lower end of the charging hopper opens into a screw conveyor 15 which conveys the material to a pipe 16 which delivers the material to conveyor 9, by which it is conveyed 30 continuously through distillation chamber 1. Conveyors 9 and 15 may be driven continuously by any suitable means, for example through pulleys 17 and 18.

Distillation chamber 1 extends entirely through 35 furnace 8 and the distillation residue is discharged into a pipe 19 through which it passes into a collecting chamber 20, from which it is discharged through a lock chamber 21 controlled by valve members 22 and 23.

40 Collecting chamber 20, lock chambers 12 and 21, and charging hopper 10 may be connected with a vacuum pump, not shown, through pipes 24, 25, 26 and 27 provided with valves for applying the vacuum to these units according to need. 45 A stream of gas which is inert to metallic magnesium, suitably hydrogen, may be introduced into the apparatus to provide a flow for directing the flow of the magnesium vapors through pipe 2, dust removing element 3, and pipe 5, into condenser 6, and to conduct the operation in an 50 inert atmosphere. In the apparatus shown, the inert gas is introduced through pipes 28 and 29 into both ends of distillation chamber 1. As shown in Fig. 3, the inert gas may be introduced 55 as need be into lock chambers 12 and 21.

Mounted in condenser 6 is a cylindrical tube 32 the lower end of which is closed by a curved bottom, the condenser being disposed so that the incoming vapors bathe its bottom surface. 60 Mounted coaxially within tube 32 is a tube 33 also closed at its lower end and coaxially surrounding a tube 34 which is open at its lower end. Cooling fluid is introduced into tube 34, and is withdrawn from tube 33 through an outlet 35. Tube 33 is 65 mounted close to but out of contact with the wall of tube 32, so that in condensation of the magnesium vapor on tube 32 the removal of heat by the cooling medium circulated through tubes 33 and 34 takes place principally by radiation. 70 Tubes 33 and 34 are vertically adjustable within tube 32, as shown, so that the cooling action may be regulated according to need. The outlet 36 from the condenser dips into a receiver 37 mounted within furnace 8 and provided with a flow- 75 controlling valve 38. By arranging the condenser

at a level more than six meters above the outlet level, a suitable automatic barometric outlet device is obtained.

According to the provisions of the patent statutes, I have explained the principle and construction of my invention, and have illustrated and described what I now consider to represent its best embodiment. However, I desire to have it understood that, within the scope of the appended claims, the invention may be practiced otherwise than as specifically illustrated and described.

No claim is made herein to the apparatus described hereinabove and shown in the drawings, this subject matter having been transferred to a divisional application filed December 17, 1934, Serial No. 757,783.

What I claim is:—

1. The process for producing substantially pure magnesium which comprises heating material containing metallic magnesium to liberate magnesium vapor therefrom, removing the resulting vapor by a non-oxidizing gas from the heated zone, separating out dust from said vapor by provoking variations of the flow of the vapor capable of promoting deposition of the suspended solids owing to their natural gravity, and thereafter passing the vapor together with the non-oxidizing gas into a condensation zone, and cooling it to condensation point. 20

2. The process for producing substantially pure magnesium which comprises heating material containing metallic magnesium to liberate magnesium vapor therefrom, removing the resulting vapor by a non-oxidizing gas from the heated zone, separating out dust from said vapor by reversing its direction of flow, and thereafter passing the vapor together with the non-oxidizing gas into a condensation zone, and cooling it to condensation point. 35

3. The process for producing substantially pure magnesium which comprises heating material containing metallic magnesium to liberate magnesium vapor therefrom, removing the resulting vapor by a non-oxidizing gas from the heated zone, separating out dust from said vapor by reducing its velocity of flow, and thereafter passing the vapor together with the non-oxidizing gas into a condensation zone, and cooling it to condensation point. 45

4. The process for producing substantially pure magnesium which comprises heating material containing metallic magnesium to liberate magnesium vapor therefrom, removing the resulting vapor by a non-oxidizing gas from the heated zone, separating out dust from said vapor by reversing its direction and reducing its velocity of flow, and thereafter passing the vapor together with the non-oxidizing gas into a condensation zone, and cooling it to condensation point. 55

5. A process for separating magnesium from non-volatile concomitant substances which comprises passing material containing metallic magnesium continuously through a heated zone to liberate magnesium vapor therefrom, carrying away the disengaged vapor by a non-oxidizing gas from the heated zone, separating out dust from the flowing vapor by provoking variations of the flow of the vapor capable of promoting deposition of the suspended solids owing to their natural gravity, and causing the vapor to condense with intermediate liquefaction. 60

6. A process for separating magnesium from non-volatile concomitant substance which comprises passing material containing metallic magnesium continuously through a heated zone to lib- 75

erate magnesium vapor therefrom, carrying away
the disengaged vapor by a non-oxidizing gas from
the heated zone, separating out dust from the
flowing vapor by provoking variations of the flow
of the vapor capable of promoting deposition of
the suspended solids owing to their natural grav-
ity, and thereafter cooling it to condensation

point, premature condensation being prevented
by keeping the vapor on its way between the dis-
tillation and condensation zone at a temperature
above the solidification temperature of metallic
magnesium.

FRITZ HANSGIRG.
